CLAIM

The ornamental design for a mule as shown and described.

DESCRIPTION

1. Mule
2. Mule
- 1.1 : Perspective
- 1.2 : Right
- 1.3 : Top
- 1.4 : Left
- 1.5 : Back
- 1.6 : Bottom
- 1.7 : Front
- 2.1 : Perspective
- 2.2 : Left
- 2.3 : Top
- 2.4 : Right
- 2.5 : Back
- 2.6 : Bottom
- 2.7 : Front

The broken lines showing the sole of the mule form no part of the claimed design.
